UNITED STATES PATENT OFFICE.

GEORGE A. E. BARNES, OF DEPEW, NEW YORK.

DESIGN FOR A SIGN.

SPECIFICATION forming part of Design No. 29,193, dated August 9, 1898.

Application filed September 7, 1897. Serial No. 650,855. Term of patent 34 years.

To all whom it may concern:

Be it known that I, GEORGE A. E. BARNES, a citizen of the United States, residing at Depew, in the county of Erie and State of New York, have invented and produced a new and original Design for a Sign, of which the following is a specification, reference being had to the accompanying drawings, forming a part thereof.

10 This design relates to the configuration of a sign intended for the use of barbers.

In the accompanying drawings, Figure 1 is a front view of a sign embodying my design. Fig. 2 is a side or edge view thereof. Fig. 3 is a horizontal section in line 3 3, Fig. 1.

15 Like letters of reference refer to like parts in the several figures.

The leading or material feature of my design consists of the representation of various 20 barbers' accessories arranged and connected in substantially the relation shown in the drawings.

A represents the figure of an open razor arranged with its hinge downward and forming the lower portion of the sign, and B represents a divided or sectional comb arranged

horizontally between the handle and the blade of the razor. Interposed between the sections of the comb is the outline figure of a shaving-mug C, and below the latter and represented as suspended therefrom is a hair-brush D. Above the comb is the figure of a pair of open scissors, represented as resting with their blades upon the comb, as shown in the drawings. 30

F is a rod spanning the space between the eyes G of the scissors, and H is the figure of a hair-clipper arranged in the triangular space inclosed by the arms of the scissors and the rod H and represented as suspended from 40 said rod.

What I claim is—

The design for a sign, substantially as herein shown and described.

Witness my hand this 20th day of August, 45 1897.

GEORGE A. E. BARNES.

Witnesses:

JOHN COFFED,
ALBERT BAME,
S. JAY OHART.
